UNITED STATES PATENT OFFICE.

NICHOLAS BARRY, JR., OF MUSCATINE, IOWA.

BUTTON-MAKING MACHINE.

SPECIFICATION forming part of Letters Patent No. 643,587, dated February 13, 1900.

Application filed May 11, 1899. Serial No. 716,412. (No model.)

To all whom it may concern:

Be it known that I, NICHOLAS BARRY, Jr., of Muscatine, in the county of Muscatine and State of Iowa, have invented certain new and useful Improvements in Button-Making Machines; and I hereby declare that the following is a full, clear, and exact description thereof, reference being had to the accompanying drawings, which form part of this specification.

This invention is an improvement in machines particularly designed for finishing button-blanks, and the machine shown in the drawings is a button-dressing machine; but the invention is readily adaptable for dressing, facing, drilling, and finishing machines.

The invention therefore consists in the combinations and constructions of parts set forth in the claims, and the accompanying drawings illustrate a button-facing machine embodying the invention and minor improvements incidental thereto, all of which will be clearly understood from the following description, taken in connection with said drawings, in which—

Figure 1 is a side elevation of the complete machine. Fig. 2 is a rear elevation thereof. Fig. 3 is a central vertical longitudinal section through the machine. Fig. 4 is a transverse section on line 4-4, Fig. 3, looking upward. Fig. 5 is a transverse section on line 5-5, Fig. 3. Fig. 6 is a sectional view of the sleeve and chuck for holding the blank. Fig. 7 is a detail perspective view of a portion of the tool-carrier disk, showing the adjusting device for the sleeve in which the tool-holding tubes play.

The base of the machine, as shown, consists of a three-armed spider A, having a central hub in which is stepped and supported the lower end of a tubular shaft B, the upper end of which is guided and journaled in the hub of a spider A', similar to the base, but inverted and supported on the latter by the connecting-rods A², by which the frame is rigidly bound together.

On the lower end of shaft B just above base A is keyed a worm-gear C, which meshes with a worm C', the shaft of which is journaled in suitable bearings C², attached to the base A, as shown, and this worm-shaft is driven by means of a pulley C³ and belt c from a pul-

ley d, attached to a large belt-pulley D and therewith journaled on a stub-shaft rigidly secured to a bracket D', which is adjustably secured to one of the uprights A² of the main frame. On shaft B above gear C is also rigidly secured a pair of disks E E', which are rigidly united and rotate as one with shaft B. In the peripheries of these disks are formed vertical journal-bearings having removable caps e', as shown, and in said journals are mounted vertical sleeves F, which are provided with collars F' on their upper ends, by which they may be suspended on the upper disk E and extend through and below the disk E', as shown. Within these sleeves are button-holding chucks G, which extend entirely through the sleeves and are provided with split and tapered upper ends which project above the collars of the sleeve and are adapted to receive the button-blanks, while their lower ends are rounded off, as shown. The chucks G are splined to the sleeves F, so as to rotate therewith, but are capable of longitudinal movement within the sleeve. The said chucks and sleeves are preferably constructed substantially as described in my application for patent on chuck, Serial No. 715,199, filed May 1, 1899, to which I refer for more particular explanation thereof. The sleeves F are provided with combined weights and pulleys f intermediate the disks E E', so that their weight will tend to hold the chucks down and cause the sleeves to close the chucks when the chucks are pushed upward through the sleeves, substantially as described in my aforesaid application.

Below the disk E' and above the screw C' is an annular cam-plate I, upon which the lower edges of the chucks G rest. In the machine shown there are ten chucks, and this cam-plate I is provided with a raised portion I', extending for about two-thirds of its diameter, and with a depressed portion I² for the remaining portion of its diameter, the upper and lower parts of the cam-plate being connected by the rising and falling portions i i'. The cam-plate I is fixed; but it is obvious that as the series of chucks is traveled there-over each chuck will be alternately raised and depressed, according to whether it travels on the high or low portion of the cam-plate. A part I³ of the lower portion I² of

the cam-plate is preferably made removable, and any chuck may be removed from the holder by simply rotating the latter until such chuck is over the part I^3 , which may be 5 removed and permit the chuck to drop vertically out of the sleeve. By this means the chucks may each be removed and changed when desired with facility.

Upon shaft B, above plate E, is a tool-carrier disk J, having a number of tool-holders constructed substantially as shown in my application for tool-holder, filed April 19, 1899, Serial No. 713,576, each holder having a vertical sleeve portion j , provided with a bifurcated tang j' , which passes between guides J^3 upon the top of disk J, with its bifurcations embracing a bolt J^2 on the disk. The guides J^3 are provided with bolts J^4 , by which the holder can be accurately positioned laterally. 10 The tool-holding tubes K are vertically movable in the sleeves j , but in the construction shown are not rotatable and are provided with weights K', by which they are depressed by gravity, the construction and operation of 15 these tool-holders being substantially such as is described in my aforesaid application, Serial No. 713,576.

The tool-holder J is rotatable with the shaft B, but is capable of a slight vertical movement thereon to permit automatic sharpening of the tools. As shown, it is splined to the shaft B by means of a pin b , passing through a slot b' in shaft B and transfixing a shaft L within and extending above the upper end of shaft B and carrying on its upper end a large wheel M, which is ratcheted on its upper surface, as at M', and is engaged by a dog m, connected to the upper end of a lever m' , which is pivoted on an arm B^3 , projecting from shaft B. The lower end of this lever is adapted to contact with an adjustable bolt A', tapped into the upper spider A', so as to oscillate the lever m' as it is moved therewith by the rotation of shaft B. The 30 position and extent of movement of lever m' can be regulated by a screw m^3 , tapped through an extension B^6 on arm B^3 . The rocking of lever m' causes dog m to turn wheel M very slightly while it is being rotated with the shaft B, and thereby move shaft L longitudinally relatively to shaft B, and as shaft L is screw-threaded into the hub of wheel M, as shown at L ^{6} , consequently each time the ratchet M is actuated by the 35 lever m' shaft L and tool-holder J are lowered slightly. This is for the purpose of resurfacing or grinding the tools k after each operation, each tool being presented once during each of its orbital movements to the 40 action of a grinder O, which is mounted on a stub-shaft O', having journals in a bracket O ^{2} , attached to the frame, and having a pulley O ^{3} , by which it is driven by a belt o from a suitably-driven pulley o', also mounted on 45 bracket o ^{2} , brackets O ^{2} and o ^{2} being adjustably secured to one of the uprights A ^{2} of the frame, as shown.

A spring J ^{5} may be interposed between the tool-holder J and the upper spider A' to assist in holding down the tool-holder, if desired. 70 Between the tool-carrier J and the chuck-carrier (i. e., disks E E') is a tool-setting plate P, which is loose on the shaft B, so that it can be turned slightly thereon, although it will normally rotate therewith. It is provided 75 with a series of notches p in its periphery, which permit the chucks G to present the blanks to the tools k during the normal operation of the machine. When it is desired to set the tools, the plate P is turned until its 80 projections p' are opposite the tool-holders K, and then the latter are adjusted inwardly until the tools k are stopped by projections p' on the setting plate. Then the tool-holders are made fast in position. This plate P therefore insures a proper setting of the tools in 85 an easy and expeditious manner.

On two of the uprights A ^{2} are journaled loose horizontally-disposed pulleys Q Q', and on the intermediate upright, to which the 90 bracket D' is attached, is another bracket R', provided with a stub-shaft, on which is journaled a belt-pulley R. The driving-belt S comes from a counter-shaft or prime mover (not shown) down under pulley D, is given a 95 quarter-turn and led to and around the pulley Q', and thence is brought back partly around the periphery of the chuck-carrier to the other pulley Q and contacts the outer peripheries of the pulleys of the several chucks 100 intervening between the pulleys Q Q'. It is then brought back toward pulley R, given a quarter-turn, and passed around pulley R up to the prime mover, so that by a single belt a 105 number of the chucks are driven. Only those 110 chucks are driven whose pulleys are brought into contact with that portion of the belt S between the pulleys Q Q', and those chucks whose pulleys f are not in contact with the belt will not rotate. As the machine is arranged all the chucks which are traveling along the raised portion I' of the cam will be 115 rotated during such travel by the belt S, while those of the chucks which are traveling over the part I ^{2} of the cam-plate will not be rotating and will be open and may be supplied with blanks by the operator while passing along the portion I ^{2} of the cam-plate. As the chuck travels over the rising portion i it is 120 lifted and its tapered upper end engages the tapered upper end of the bore of the sleeve F and lifts the latter, with its pulley, as indicated in the drawings, the weight of the sleeve and the pulley being sufficient to close the chuck tightly on the blank, as described in 125 my application, Serial No. 715,199, aforesaid. As soon as the chuck reaches the upper portion I' of the cam-plate its pulley f strikes the belt S, and thus the chuck is rapidly rotated on its axis while it is traveling 130 over the part I' of the cam-plate. As the chuck reaches the descending portion i' of the cam-plate its pulley passes out of contact with the belt S, and consequently the chuck stops

rotating and the weight of the sleeve and the pulley causes the chuck to drop, and as the chuck can drop farther than the sleeve, which is arrested by its collar F', it releases the blank, which is then removed mechanically. A suction-tube T may be employed to remove the blanks from the holders, as indicated in Fig. 1 of the drawings.

It should be particularly noted that each blank holder or chuck has its corresponding tool-holder, there being one tool-holder for each chuck, and such tool-holder always maintains its position relatively to the chuck—that is, it travels therewith during the operation of the machine. In the machine shown the tool-holder and the chuck-holders are supposed to travel continuously; but whether they travel continuously or step by step the tool-holder always moves with its chuck, and vice versa, and this, as stated at the outset, I consider a most valuable feature of the invention, because after the tool-holder is once adjusted relatively to the chuck there is no uncertainty in the operation, as there would be if the chucks presented the blanks successively to different tools or different holders were successively brought to operate in connection with the chuck. In my machine the chucks and the holders are in pairs, the same holder always working with the same chuck, and vice versa, and it is this correlation and co-operation continuously maintained in the machine which I consider of the greatest importance therein and produces absolute uniformity in operation and product.

To recapitulate briefly the operation of the machine, it is started and the chuck-holder and tool-holder rotated, preferably continuously or step by step, and those of the chucks whose pulleys f contact with the belt S are rotated on their axes while they describe a circular orbit around the shaft. Those of the chucks whose pulleys are free of the belt and are passing over the lower portion I' of the cam-plate are ready to receive the blanks, which are fed thereto by the operator. Then as they ride up on the incline i the chuck is raised and in so doing is closed by the weight of its sleeve and pulley which is lifted by it, and as the chuck travels along part I' of the cam-plate its pulley is brought into contact with the belt S and the chuck rotated and simultaneously the blank is brought into contact with the tool. The tool-holders being weighted are free to drop by gravity until the blank is properly dressed. When the blanks first touch the tool, they lift it up and it cuts the blank more or less rapidly, according to the weight of the tool-holder, as described in my application, Serial No. 713,576, aforesaid. The trimming operation may continue during the entire time the chucks are traversing the portion I' of the cam-plate, which insures ample time for the complete dressing of the blanks. The descent of the tool-holder is limited, so that the blank cannot be injured if the cutting or dressing is completed before

the chuck has traversed the part I' of the cam-plate. When the chuck reaches the descending portion i, it opens and the button is removed and a new blank inserted, while the chuck moves along the part I² of the cam-plate.

Having thus described my invention, what I therefore claim as new, and desire to secure by Letters Patent thereon, is—

1. In a button-making machine, the combination of an annular series of rotary blank-holders and an annular series of radially-adjustable tool-holder supports fixed relatively to the blank-holders, and vertically-movable tool-holders in said supports said holders dropping by gravity, and means for traveling the same together; with means for rotating said holders during their travel whereby the blank is operated upon without stopping the travel of the parts.

2. In a button-making machine the combination of a continuously-traveling rotatable blank-holder, a non-rotatable gravitational tool-holder co-operating and traveling with said blank-holder, and adapted to present the tool to the blanks by gravity during part of the orbital travel of the blank and tool holders substantially as described.

3. In a button-dressing machine, the combination of a series of rotatable blank-holders, and means for orbitally traveling the same, a non-rotatable tool-holder for each blank-holder co-operating and traveling therewith, and means for rotating the blank-holders during that part of their travel in which the blanks are subjected to the action of the tools, substantially as described.

4. In a button-making machine the combination of a rotatable chuck-carrier, a chuck removably mounted therein, a rotatable tool-carrier, a non-rotatable tool-holder mounted thereon relatively to and traveling with the chuck, and means for bringing the blank into contact with the tool during part of the travel of the chuck and tool.

5. In a button-making machine, the combination of a rotatable chuck-carrier, a rotatable chuck mounted thereon, a rotatable tool-carrier, a non-rotatable tool mounted thereon relatively to and traveling with the chuck, means for rotating said chuck during a part of its travel, and means for bringing the blank into contact with the tool to finish the blank during such part of the travel of the chuck.

6. The combination of a rotatable chuck-carrier a series of removable and rotatable chucks journaled thereon, a tool-carrier opposite and movable with the chuck-carrier, and a series of gravitational tool-holders thereon, one for and opposite each chuck; with means for rotating the chucks during a part of their orbital movement and means for causing the chuck to present the blank to the tool during such part of the orbital movement of the chuck.

7. The combination of the rotary disk, the series of tool-holders carried thereby, and a

- sharpening device fixedly mounted on the frame of the machine in the path of the tools, and adapted to successively sharpen each tool during its travel therepast without stopping the machine, and means whereby the relative positions of the tools and sharpeners are altered for each rotation of the disk, substantially as described.
8. The combination of the rotary disk, the series of adjustable tool-holders carried thereby, an inclined rotary sharpening-disk fixedly mounted on the frame of the machine in the path of the tool adapted to successively sharpen the tools during their orbital movement therepast without stopping the machine, means for rotating said disk, substantially as described, and means whereby the relative positions of the tools and sharpeners are altered for each rotation of the disk, substantially as described.
9. The combination of a rotatable chuck-carrier, a rotatable chuck journaled in said holder, a tool-carrier opposite and moving with the chuck, means for rotating the chuck during part of its orbital movement, and means for lifting the chuck during its rotation so as to present the blank to the action of the tool.
10. The combination of the rotary chuck-carrier, a series of rotatable chucks thereon, a tool-carrier above and rotatable with the chuck-holder, the tools mounted thereon, one for and opposite each chuck, means for rotating the chucks during part of their orbital movement, and means for lifting the chuck during its rotation so as to present the blank to the action of the tool, for the purpose and substantially as described.
11. In a button-making machine, the combination of the vertical shaft, the disks thereon, the vertically-movable and rotatable sleeves journaled in said disks and provided with pulleys, the chucks guided in said sleeves, and a cam-plate below the disk by which the chucks are supported and guided, substantially as described.
12. In a button-making machine, the combination of the rotatable vertical shaft, the disks thereon, the vertically-movable and rotatable sleeves journaled in said disks and provided with pulleys, and the chucks guided in said sleeves, with a fixed cam-plate below the disk upon which the chucks are supported and guided as they are traveled thereover, and means for rotating said chucks during part of their orbital movement.
13. In a button-making machine, the combination of the vertical shaft, the disks thereon, the vertically-movable chucks on said disks, a cam-plate below the disks upon which the chucks are supported and guided, and means for rotating said chucks, a tool-holding disk above the chucks, and the adjustable tool-holders on said disk, one for and opposite each chuck, substantially as described.
14. In a button-making machine, the combination of the vertical shaft, the disks thereon, the vertically-movable sleeves journaled in said disks and provided with pulleys, the chucks guided in said sleeves, a fixed cam-plate below the disk upon which the chucks are supported and guided, and means for rotating said chucks during part of their orbital movement, a tool-carrier above the chucks and rotatable therewith, and the adjustable tool-holders on said carrier, one for and opposite each chuck, substantially as described.
15. The combination of the tool-carrying disk, the adjustable tool-holders attached to said disk and the tool-setting plate below the disk whereby said tool-holders can be set, substantially as described.
16. The combination of the rotatable tool-carrier the adjustable tool-holders attached thereto and the adjustable tool-setting plate below and rotatable with the carrier, whereby said tool-holders can be set for the purpose and substantially as described.
17. The combination of the rotatable disk, an annular series of tool-holders mounted thereon, the rotatable shaft carrying said disk, a shaft for rotating said disk, a shaft telescoping within the rotatable shaft and supporting the disk, a ratchet-wheel supported on the upper end of said outer shaft and having an interiorly-threaded hub engaging the threaded upper end of said inner shaft, and devices adapted to engage said ratchet and impart a slight rotary movement to the wheel relatively to the outer shaft, whereby the tool-holder is gradually moved longitudinally of the outer shaft, substantially as described.
18. The combination of the rotatable disk, an annular series of tool-holders mounted thereon, provided with tools, the rotatable shaft carrying said disk, a shaft for rotating said disk, a shaft telescoping within the rotatable shaft and connections between said inner shaft and the disk; with a ratchet-wheel threaded on the upper end of said inner shaft, and devices adapted to engage said ratchet and impart a slight rotary movement to said wheel relatively to the outer shaft, and a sharpening device projecting into the path of the tools and adapted to sharpen each tool once during the orbital movement thereof, for the purpose and substantially as described.
19. The combination of a rotary shaft, a pair of disks on said shaft, sleeves journaled in said disks, and provided with pulleys, a drive-belt on the frame of the machine adapted to engage said pulleys during part of the orbital movement thereof and rotate the sleeves, the chucks rotatable with said sleeves but longitudinally movable therein, the fixed cam-plate below the chucks adapted to support the latter in the sleeves, the tool-holding disk above the chucks, the series of tool-holders thereon, one opposite each chuck and maintaining a fixed relation thereto, and means for moving said tool-holding disk ver-

tically, and a sharpener on the frame of the machine adapted to sharpen the tools after each operation thereof.

20. The combination of the frame, a vertical shaft therein, a worm-gear for operating said shaft, a pair of disks on said shaft, the sleeves journaled in said disk, provided with pulleys, the drive-belt on the frame of the machine adapted to engage said pulleys during part of the orbital movement thereof and rotate the sleeves; the chucks rotatable with said sleeves but longitudinally movable therein, the fixed cam-plate below the chucks adapted to support the latter in the sleeves, the 15 tool-holding disk above the chucks, and the series of adjustable tool-holders thereon, one opposite each chuck and maintaining a fixed relation thereto; with an inner shaft within the outer shaft, a pin connected to said inner

shaft and passing through slots in the outer 20 shaft engaging said tool-holding disk, a ratchet-wheel threaded to the upper end of said inner shaft, the oscillating lever, and connections substantially as described where- by said wheel is rotated slightly relatively to 25 the outer shaft at each rotation thereof, so as to slightly lower the tool-holder after each rotation, and a sharpener on the frame of the machine adapted to sharpen the tools after each operation thereof, substantially as de- 30 scribed.

In testimony that I claim the foregoing as my own I affix my signature in presence of two witnesses.

NICHOLAS BARRY, JR.

In presence of—

W. H. GILBERT,
MARTIN W. STAPLETON.
